UNITED STATES PATENT OFFICE

LUIGI ORLANDO, OF MILAN, ITALY, ASSIGNOR, BY MESNE ASSIGNMENTS, TO METALURGICA BRESCIANA GIA TEMPINI, OF FIUMEGRANDE, BRESCIA, ITALY, A COMPANY OF ITALY

DEVICE FOR LOADING FIREARMS

Application filed January 3, 1930, Serial No. 418,270, and in Italy November 22, 1929.

This invention relates to devices for loading fire arms, more particularly of the light machine gun type, by which it is possible to feed cartridges to said arms in a simple, 5 rapid and economic manner.

The device comprises a magazine of any type suited to the arm in connection with which it is to be used and provided with a spring lifter for the cartridges. Its characteristic feature is that the magazine is split 10 in a longitudinal direction from its mouth to near its bottom and is so shaped that the two parts separated by said longitudinal cut may recede at will from each other to 15 the necessary extent for introducing through the mouth into the magazine a filler containing the cartridges and thereupon be drawn again towards each other so as to re-close the magazine body or box and retain the cartridges in the magazine when the filler is removed.

Another object of the invention is to provide a magazine in which the two parts separated by the longitudinal cut tend to come 25 by elasticity into the open position which permits the introduction of the filler, and a slider mounted for displacement in suitable magazine guides holds the two parts close together and thus the magazine body 30 closed when it is brought into its position nearest to the mouth, while it allows the magazine to open for introducing the filler when it is brought in proximity to the bottom of the magazine.

The fillers may be of any suitable type 35 according to the arm and magazine in use and contain cartridges on one or two rows; in practice they are manufactured by the same fire arm factory and thus distributed to 40 the gunners. The magazine may be detached from the arm for loading but it is obvious that it can also be hinged to this latter by one of the two parts into which it is subdivided by the longitudinal cut or in any 45 other suitable manner, without departing from the spirit of this invention.

The accompanying drawings shows by way of example an improved magazine according to this invention.

Figure 1 is a cross sectional view of the

magazine body closed in its operative position.

Figure 2 is a cross sectional view thereof with open body for loading by means of a 55 filler also partly shown.

Figures 3 and 4 are a side view and rear view, respectively, with closed magazine body.

Figures 5 and 6 are a horizontal section and longitudinal section, respectively, also 60 with closed magazine.

Figure 7 is a partial side view of the magazine and a filler in position ready for loading.

With reference to the drawings, the magazine is subdivided into two parts 1_1 and 1_2 in the longitudinal direction by a cut which in the example shown is formed by a cut —s— made on the back portion and by an opening —S— on the front face, both extending from the lips 2 into proximity to the bottom 3. 70

In the construction shown the magazine is wholly open on its front face from the lips into proximity to the bottom and the bullets wholly project from the magazine, the side walls whereof are formed with a constricted 75 portion 4 to correspond with the neck portion of the cartridge case in order to hold the cartridges in position.

5 denotes the cartridge lifter and 6 the spring thereof. 7 denotes the slider movable 80 on the guide ribs 8 formed on the back portion of the magazine.

When the slider 7 is in its position nearest to the lifts 2 (shown in Figs. 1, 3, 4, 5 and 6), the magazine body is rigidly closed as in a 85 usual magazine and therefore its working is as reliable as that of a magazine with undivided body.

When the slider is displaced towards the bottom 3 into the position shown in Fig. 2, 90 the two parts 1_1 and 1_2 into which the magazine is subdivided by the longitudinal cut —s—S— open by elasticity being no longer held closed by the slider (see Fig. 2) and the distance between the edges of the lips 2 is 95 such that the branches 8_1 — 8_2 of the filler can freely be introduced for loading. The filler is inserted between the lips 2 and pushed fully into the magazine pressing back the lifter 5 against the action of the spring 6. 100

When the last cartridges of the filler are underneath the edge of the lips 2, i. e. the filler is wholly introduced, the slider 7 is displaced towards the lips 2 and brought into the position shown in Fig. 1. The two halves 1₁ and 1₂ of the magazine body are thus brought close to each other and the lips 2 come over the cartridges passing between the branches 8₁ and 8₂ (Fig. 7) of the filler. When removing the filler the cartridges are prevented for slipping out by the lips 2, while the branches 8₁ and 8₂ are freely withdrawn by pulling a handle with which the filler is provided.

It is obvious that the branch 8₂ of the filler instead of extending only a short distance corresponding with the cartridge neck portion as shown in Fig. 7 may extend further in order to surround the bullets of the two cartridge rows, as shown in Fig. 2, exactly like the rear branch 8₁ which surrounds the caps of the two cartridge rows.

The magazine may be of any suitable form and size and contain one or more rows of cartridges and its lifter can be guided through pins or other extensions in slots on the side walls of the magazine body in order to prevent its falling to the outside when the magazine body is opened for its loading, without departing from the spirit of this invention.

What I claim is:

1. A loading device for fire arms comprising a box-shaped cartridge magazine having in its middle plane parallel to the cartridge axis a longitudinal cut extending from the cartridge inlet mouth into proximity to the bottom dividing the magazine into two integral resilient parts, which recede from each other when a cartridge filler is introduced into the magazine and automatically close onto the filled in cartridges when the filler is withdrawn.

2. A loading device for fire arms comprising a box-shaped magazine which is subdivided by a longitudinal cut along the axial plane parallel to the cartridge axis extending from the cartridge inlet mouth into proximity to the bottom into two lateral parts which tend to recede from each other, a slider movable on guides on said lateral parts and adapted to bring the latter close together when it is displaced towards the mouth and a filler formed in such manner that it can be introduced filled with cartridges into the magazine when the lateral parts are brought apart and extracted in an empty condition when said lateral parts of the magazine are brought together by the displacement of said slider.

3. A loading device for fire arms comprising a box-shaped magazine which is subdivided by a longitudinal cut along the plane parallel to the cartridge axis extending from the cartridge inlet mouth into proximity to

the bottom into two lateral parts which may recede from each other for filling in the cartridges and a filler filled with cartridges formed in such manner that it can be introduced into the magazine when it is filled with cartridges by moving apart said lateral portion and can be extracted in an empty condition when said lateral parts of the magazine have closed over the cartridge rows in the filler.

4. A loading device for fire arms comprising a box-shaped cartridge magazine open on its front wall along which the adjacent edges of the magazine sides are depressed for applying them against the cartridge neck portion, the rear wall of said magazine being subdivided by a cut extending from the inlet mouth into proximity to the bottom of the magazine body, guide ribs extending laterally from said rear wall, a slider movable on said guide ribs and adapted to hold the sides close to each other when it is displaced towards the magazine inlet mouth, said sides being automatically drawn apart by elasticity when the slider is displaced towards the bottom of the magazine.

5. A loading device for fire arms comprising a box-shaped cartridge magazine open on its front wall along which the adjacent edges of the magazine sides are depressed for applying them against the cartridge neck portion, the rear wall of said magazine being subdivided by a cut extending from the inlet mouth into proximity to the bottom of the magazine body, guide ribs extending laterally from said rear wall, a slider movable on said guide ribs and adapted to hold the said sides close to each other when it is displaced towards the magazine inlet mouth, said sides being automatically drawn apart by elasticity, when the slider is displaced towards the bottom of the magazine, cartridge retaining lips limited to the central portion of the inlet mouth, a filler consisting of a front and rear branch supporting the cartridges capable of being introduced filled with cartridges into the magazine, when said sides are drawn apart in order to clear the cartridge rows between said retaining lips, said retaining lips closing over the cartridge rows through the displacement of said slider towards the inlet mouth, after which said filler can be removed from the magazine in an empty condition.

In testimony that I claim the foregoing as my invention, I have signed my name.

LUIGI ORLANDO.
